Primary Examiner — Karen S Acker*Assistant Examiner* — Wendy Arminio(74) Attorney, Agent, or Firm — Kimberly-Clark Worldwide, Inc.(57) CLAIM

We claim the ornamental design for a wipe with pattern for embossing.

DESCRIPTION

The sole FIGURE shows a perspective view of a wipe with pattern for embossing.

The broken lines surrounding the design form the boundaries of the claim and form no part thereof.

The thickness of the design forms no part of the claim.
